UNITED STATES PATENT OFFICE.

HORACE W. LOVELAND, OF TOPEKA, KANSAS.

FURNACE FIRE-GRAVE AND FRAME.

SPECIFICATION forming part of Letters Patent No. 293,258, dated February 12, 1884.

Application filed May 21, 1883. (No model.)

To all whom it may concern:

Be it known that I, HORACE W. LOVELAND, a citizen of the United States, residing at Topeka, in the county of Shawnee and State of 5 Kansas, have invented a new and useful Furnace Fire-Grate and Frame, of which the following is a specification.

My invention relates to improvements in furnace fire-grates; and it consists in certain 10 features of construction and in combination of parts hereinafter described, and pointed out in the claims.

In the drawings, Figure 1 is a view in perspective of the frame for the grates and actuating mechanism, and a part of the grates in 15 position. In this view the front piece of the frame is removed. Fig. 2 is a side elevation of a grate-bar and a transverse sectional view of the frame and oscillating bars. Fig. 3 is a 20 plan view of a grate-bar. Fig. 4 is a transverse section of the same.

A and B are the side pieces of the supporting-frame for the grate-bars, and are joined by the front and back pieces, C and C'. The side 25 pieces have lugs at each end extending below, as at a, in which are pivoted the oscillating cross-bars D and D'. These oscillating bars have, respectively, the arms d and d', and the bar D has also the lug d'', provided with a hole 30 for engaging the removable lever d''. The side piece A has at the central part an arm, d', extending below and supporting the lever E, that is pivotally attached thereto near the center thereof, as shown. The lower end of 35 the lever E is connected by the rod e to the arm d, while the upper end of the lever is connected by the rod e' to the arm d'. The grate-bars F, as shown in Fig. 2, are notched at one end on the lower side, to engage the up- 40 right leg of the oscillating bars, while the other end of the grate-bar has a lug, f, resting on the horizontal leg of the said oscillating bars. When in position, alternate grate-bars have their notched ends at the right hand, 45 while the intervening bars have their notched ends to the left hand.

The operation of the device is as follows: By means of the lever d'' the bar D is oscillated or rocked, and this oscillating motion 50 by means of the lever E and the rods e and e' is conveyed to the bar D', but in an opposite

direction—to wit, when the upright leg of the bar D moves to the right the upright leg of the bar D' will move to the left hand, and vice versa. The alternate grate-bars, whose 55 notched ends engage the bar D, will reciprocate simultaneously with, but in an opposite direction from, the intervening bars, whose notches engage the bar D'. The grate-bars reciprocated by the bar D are at each reciprocation raised and lowered at the other or left-hand end by means of the lugs f, engaging the horizontal leg of the bar D'. In like manner the intervening grate-bars reciprocated by the lever D' are raised and lowered at their right-hand end by the engagement of the respective lugs f with the horizontal leg of the bar D. This movement endwise and in opposite directions of contiguous grate-bars, together with the vertical movement described of the 60 opposite ends of the said contiguous grate-bars, prevents the clinkers from attaching to the grate-bars, and also breaks and crushes the clinkers into such small fragments that they are, together with the ashes, readily discharged 65 through the spaces between the said grate-bars. This, too, is accomplished without opening the furnace-doors or in any way retarding the process of combustion. The lever d'' may be operated through a slot in the fire-front or 70 through the open ash-pit door.

What I claim is—

1. In furnace grate-bars, oscillating cross-bars, each provided with an upright and a horizontal leg, and so arranged that the respective horizontal legs extend toward each other, and provided with suitable connecting mechanism, so that the two cross-bars will oscillate simultaneously and the respective upright legs move in opposite directions, sub- 85 substantially as and for the purpose set forth.

2. Furnace grate-bars provided at one end with a notch adapted to engage the upright leg of the oscillating cross-bar, and the other end of the grate-bar provided underneath with 90 a flat surface and a lug, the former adapted to slide on the contiguous cross-bar, and the latter adapted to engage the horizontal leg of the said cross-bar, so as to be actuated vertically thereby, substantially as described, and 95 for the purpose set forth.

3. In furnace grate-bars, oscillating cross-

bars, each provided with an upright and a horizontal leg, and connected by suitable mechanism, so that the cross-bars will oscillate simultaneously, but in opposite directions, in combination with grate-bars provided on the under side with a notch at one end and a flat surface and a lug at the other end, and so arranged that alternate grate-bars will engage with their notched ends opposite cross-bars, so that when the said cross-bars are oscillated contiguous grate-bars will move endwise in

opposite directions, and will be actuated vertically at opposite ends, substantially as described, and for the purpose specified.

4. The combination, with furnace grate-bars, substantially as described, of the cross-bars D and D', provided with the actuating mechanism E, e, and e', and the lever d³.

HORACE W. LOVELAND.
